HIS ATTORNEY

UNITED STATES PATENT OFFICE.

FREDERICK W. RUDLIN, OF PHILLIPSBURG, NEW JERSEY, ASSIGNOR TO INGERSOLL-RAND COMPANY, OF JERSEY CITY, NEW JERSEY, A CORPORATION OF NEW JERSEY.

ROCK DRILL.

Application filed October 30, 1926. Serial No. 145,274.

This invention relates to rock drills, but more particularly to a distributing valve for fluid actuated rock drills of the hammer type.

5 The objects of the invention are to obtain a quick and positive valve action and to utilize exhaust pressure fluid for holding the valve in thrown position.

Other objects will be in part obvious and 10 in part pointed out hereinafter.

The invention consists of the combination 15 of elements, features of construction and arrangement of parts having the general mode of operation substantially as herein-after pointed out in the appended claims and illustrated in the accompanying drawings, in which

Figure 1 is a longitudinal elevation in 20 section of so much of a rock drill as will serve to illustrate the invention, and

Figure 2 is a similar view showing the valve and the piston in another position which they may assume in operation of the drill.

25 Referring to the drawings, A designates a cylinder closed at its front end by a bushing B and at its rearward end by a back head C. Disposed within the cylinder A is a hammer piston D having in this instance 30 a plain reduced extension E which cooperates slidably with a bore F in the bushing B.

Disposed on the cylinder A is a valve chest G having a longitudinal bore H there-through. Bushings J are disposed in the 35 ends of the bore H and are provided at their outer ends with flanges K which seat into recesses L formed in the ends of the bore H. The bushings J are suitably bored 40 to form a valve chamber O closed in this instance at its ends by plugs P having suitable flanges Q to abut the ends of the bushings J. The bushings J and the plugs P may be held in assembled position in any 45 suitable manner.

In the present instance pressure fluid may be admitted from a suitable source of supply to the valve chest G through a connection R from which connection branch in opposite 50 directions, supply passages S. These supply passages S communicate with the valve chamber O through ports T and U formed in the rearward and front bushings J respectively. Ports V and W preferably

formed diametrically opposite the ports T and U communicate with rear and front inlet passages X and Y of the cylinder through passages Z.

Formed in the bushings J preferably near the ends of the chamber O are ports b for establishing communication between the inlet passages X and Y and the ends of the chamber O. Similar ports c are formed in the opposite sides of the bushings J to register with main exhaust ports d in the valve chest leading to the atmosphere.

Disposed within the valve chamber O is a distributing valve e having in this instance a central head f and end heads g and h. The heads are of the same diameter and the outer heads g and h control both the admission of pressure fluid from the supply passages S to the ends of the cylinder and also the exhaust of pressure fluid from the ends of the cylinder to the atmosphere, while the central head f serves to prevent the simultaneous exposure of the inner ends of the heads g and h to pressure fluid and which pressure fluid would act to centralize the valve in the valve chamber. The end heads g and h are preferably so spaced with respect to each other that the valve will be unable at any time to completely cover both the inlet ports which they control. However, the end heads are of such length that either head may simultaneously cover the inlet ports and the exhaust ports which they are adapted to control.

Leading from a point rearwardly of the median line of the cylinder to the rearward end of the valve chamber O is a passage j controlled in this instance by the piston for delivering pressure fluid to the rearward end of the valve to throw the valve forwardly to the position shown in Figure 2. A similar passage k leads from a point forwardly of the median line of the cylinder to the front end of the valve chamber O for conveying pressure fluid thereto to throw the valve rearwardly. Preferably 90 bleeder passages o are formed in the plugs P to provide an outlet for any pressure fluid which may leak past the end heads to the ends of the valve chamber O.

In the operation of the device, with the parts in the position illustrated in Figure 1, pressure fluid entering the connection R will flow through the supply passages S,

through the port T, into the valve chamber O between the heads f and g thence through the port V, the passage Z and through the inlet passage X to the rearward end of the cylinder to impel the piston forwardly. As the piston proceeds on its forward stroke, it will uncover the kicker passage j, whereupon pressure fluid will flow through said passage j to the rearward end of the valve chamber O and move the valve e forwardly to the position illustrated in Figure 2, thus covering the ports T and V and simultaneously uncovering the ports b and c to permit the escape of pressure fluid from the rearward end of the cylinder through these channels and through the main exhaust port d and the end of the valve chamber to the atmosphere. The exhaust fluid thus flowing through the valve chamber will act against the forward end surface of the valve and hold said valve in its rearward position. While the valve is in its rearwardmost position the front end of the cylinder will be opened to the atmosphere so that any air which may exist in the front end of the cylinder will be expelled through the front inlet passage Y, the ports b and c and the main exhaust port d to the atmosphere, thus preventing the upbuilding of compression in the front end of the cylinder.

Upon the forward movement of the valve e the front end head h will uncover the front supply passage S to admit pressure fluid between the heads g and h and through the port W, the front passage Z and the front inlet passage Y to the front end of the cylinder to impel the piston rearwardly. During the rearward stroke of the piston the front kicker passage k will be uncovered and pressure fluid will then pass through this passage to the front end of the valve chamber O and throw the valve e to its rearwardmost limiting position. In the rearward position of the valve communication between the ports U and W will be cut off by the head h and the front end of the cylinder will again be opened to the atmosphere through the inlet passage Y, the ports b and c and the main exhaust port d, thus completing the cycle of operations.

From the foregoing, it will be observed that the valve is thrown by live pressure fluid and is held in thrown position by pressure fluid exhausting from the cylinder. This is a desirable advantage in valves of this type for the reason that the valve may be thrown at the most desirable period in the cycle of operations.

I claim:

1. In a fluid actuated rock drill, the combination of a cylinder, a hammer piston in the cylinder, a valve chest having a valve chamber and a pair of supply passages, inlet passages leading from the valve chamber to the ends of the cylinder, ports in the valve chest for exhausting pressure fluid from the ends of the cylinder into the ends of the valve chamber, main exhaust passages leading from the ends of the valve chamber for conveying such exhaust fluid to the atmosphere, a valve in the valve chamber having a central head and end heads, the end heads controlling the inlet and exhaust passages and being spaced with respect to each other to prevent simultaneous covering of the inlet passages, and kicker ports leading from opposite sides of the median line of the cylinder to corresponding ends of the valve chamber for conveying pressure fluid to the ends of the valve chamber for throwing the valve, said valve being held in thrown position by exhaust fluid acting on the end surfaces of the valve.

2. In a fluid actuated rock drill, the combination of a cylinder, a hammer piston in the cylinder, a valve chest having a valve chamber and a pair of supply passages, inlet passages leading from the valve chamber to the ends of the cylinder, ports in the valve chest for exhausting pressure fluid from the ends of the cylinder into the ends of the valve chamber, main exhaust passages leading from the ends of the valve chamber for conveying such exhaust fluid to the atmosphere, a valve in the valve chamber having a central head and end heads, the end heads controlling the inlet and exhaust passages and spaced with respect to each other to prevent coincident covering of the inlet passages and the central head serving to prevent simultaneous exposure of the inner surfaces of the end heads to pressure fluid, kicker ports leading from opposite sides of the median line of the cylinder to corresponding ends of the valve chamber for conveying pressure fluid to the ends of the valve chamber for throwing the valve, the valve being held in thrown position by exhaust pressure fluid passing through the ends of the valve chamber and acting against the end surfaces of the valve, and bleeder ports leading from the ends of the valve chamber to the atmosphere.

In testimony whereof I have signed this specification.

FREDERICK W. RUDLIN.
